UNITED STATES PATENT OFFICE.

JOHN R. GAMMETER, OF AKRON, OHIO, ASSIGNOR TO THE B. F. GOODRICH COMPANY
OF NEW YORK, N. Y., A CORPORATION OF NEW YORK.

VULCANIZER.

1,191,296.

Specification of Letters Patent. Patented July 18, 1916.

Continuation of application Serial No. 629,274, filed May 25, 1911. This application filed February 8, 1916.
Serial No. 76,884.

To all whom it may concern:

Be it known that I, JOHN R. GAMMETER, residing in the city of Akron, county of Summit, and State of Ohio, have invented 5 certain new and useful Improvements in Vulcanizers, of which the following is a specification.

This invention relates to vulcanizers designed primarily for curing articles of rubber by surrounding the molds with a heated 10 fluid under pressure, such as steam.

The invention is, for example, adapted to presses of the vertical type, in which a number of molds containing rubber tires or similar 15 articles are retained and vulcanized at one operation. Presses of this nature as heretofore constructed have comprised a shell in which the molds are contained and subjected to the action of steam, this shell 20 being closed at the top by a cover which may be removed to permit the charging and discharging of the press. For lifting the molds out of the chamber or shell, or lowering them thereinto, a hydraulic ram or 25 equivalent means is used, this ram being utilized also to clamp the molds against the cover, which is firmly locked to the top of the shell and forms an abutment.

In vulcanizers of this type, as well as 30 others employing internal pressure against the cover or door, the locking of the cover to the shell by a small exertion of power but with sufficient tightness to prevent separation and consequent leakage has presented 35 many difficulties which it is the object of the present invention to overcome. My invention does away with the necessity for a tight clamping of the cover upon the shell by the use of a packing of such a nature 40 and so disposed with relation to the interfitting parts as to seal the joint between these two parts whether one is tightly closed upon the other or not.

The invention also contemplates certain 45 improvements in details of structure to be hereinafter pointed out.

This application is a continuation of my application Serial Number 629,274 for the same subject-matter, filed May 25, 1911.

50 In the accompanying drawings, which form a part of this specification, Figure 1 is a view partly in vertical section and partly in side elevation of a vulcanizer embodying my invention, the parts being

shown in position for charging and dis- 55 charging the same; Fig. 2 is a view partly in plan and partly in horizontal section, showing the cover in unlocked position and the plunger head operatively connected with the cover and mold-carrying frame; Fig. 3 60 is a view similar to Fig. 2, the cover and mold-carrying frame being shown rotated in order to lock the former, and disengage the latter from the plunger head; Fig. 4 is a view partly in vertical section and partly in 65 elevation of the parts shown in Fig. 1; but taken at right angles to the position at which Fig. 1 is taken, the parts being in the position shown in Fig. 2; that is, with the cover unlocked and the plunger head 70 in engagement with the supporting frame, ready to lift the latter, the cover and the molds; Fig. 5 is a view similar to Fig. 1, the parts being shown in the position illustrated in Fig. 3, the cover being locked in 75 position and the molds being compressed between the same and the plunger head; Fig. 6 is a detailed view illustrating a portion of the cover in locked engagement with the shell, showing the anti-friction bearing 80 for supporting the cover and the means for sealing the joint between the cover and shell; Fig. 7 is a detailed sectional view showing the improved packing for the ram. 85

In these drawings I have illustrated but 85 one specific form of my invention, but I do not wish to be limited to the exact structure therein shown, as this invention may be embodied in vulcanizers of various other forms, having the general type of door or 90 cover locking means described, and employing an internal, outwardly-acting pressure tending to open the door or cover.

Referring to the drawings in detail, the 95 numeral 1 designates the shell or casing of the vulcanizer, which has riveted or otherwise suitably secured to its lower end a massive flanged ring 2 resting upon the base plate 3 which supports the vulcanizer. The cylinder 4 of the hydraulic ram is provided with a flange 5 which rests upon the flanged portion of the ring 2. A plunger 6 works in the cylinder 4 and is provided at its upper end with an enlarged head 7 which will be more fully described hereinafter. The 100 upper end of the shell 1 has secured to it a ring 8 having in its inner face a groove 9, the upper wall of the groove being 105

notched as indicated at 10, the remainder of the wall forming a series of inwardly projecting lugs 11.

12 is the cover of the vulcanizing chamber, this being preferably formed of cast metal provided with depending strengthening webs 13 which engage the uppermost mold during the vulcanizing operation, and, in addition to their strengthening action, 16 permit the free circulation of steam above the mold. The cover 12 is provided with a series of radially projecting lugs 14 adapted to pass through the notches 10, when being applied or removed, and when the cover is rotated through a fraction of a revolution, 20 to engage beneath the lugs 11. A slight rotation of the cover thus serves to lock or unlock the same. The groove 9 is preferably somewhat wider than the thickness of the lugs 14, so as to permit the latter to slide easily beneath the lugs 11 when the cover is rotated. To further facilitate the rotation of the cover, an anti-friction bearing for the latter is preferably provided. Such a bearing 25 is illustrated in Fig. 6. As there shown, I form in the bottom 15 of the groove 9 a groove or ball race 40 in which are balls 41. The balls are retained in their race by a ring 42 upon which the lugs 14 rest when the 30 cover is lowered into position. The cover when rotated carries with it the ring 42 which rolls freely upon the balls. The cover may be rotated by suitable means provided for that purpose, such as one or more 35 gear segments 16 secured thereto engaged by pinions 17 journaled upon the ring 8 secured to the shell. For rotating the pinions the latter may be provided with upwardly projecting hubs 18 perforated at 19 for the 40 reception of bars or other suitable means for turning the same. Depending from the cover 12 is a frame adapted to support the molds 20 during the charging and discharging of the press, this frame also being utilized to lift the cover. The frame preferably 45 comprises four rods 21 provided with collars 22 which engage beneath the cover and nuts 23 screwed on the upper end of the rods and engaging the top of the cover. 50 The lower ends of the rods are joined by a horizontal ring or frame 24. A pair of racks 25 are supported one between each pair of the rods 21, the upper ends of these racks being bolted to the cover and the lower 55 ends to the ring 24. These racks are provided with one or more series of steps or shoulders 26 adapted to be engaged by portions of mold-carrying grids or trays 27, the trays being provided with eyes 28 through 60 which the rods 21 pass. The grids or trays are maintained in vertical alinement by these rods and are prevented from dropping, each below a predetermined position, by means of suitable stops with which each is 65 provided, adapted to engage corresponding

pairs or shoulders on the racks 25. The grids or trays are, however, free to move upwardly toward the cover 12 in order to permit the molds which are interposed between them to be subjected to compression 70 by the ram 6 or to permit some of the grids to be brought into contact in case it is desired to operate the press at less than its full capacity. The construction and mode of operation of these racks and trays is fully 75 illustrated and described in United States Letters Patent Number 758,863, granted May 3, 1904, to Edwin Coupland Shaw, and their operation need not be more fully set forth herein. This structure, while advantageously used with my invention, is not an essential part thereof, and may in some cases be dispensed with.

In order that the ram may be free at proper times to compress the molds between 85 the plunger head and the cover, and at other times to remove the cover and lift the molds from the vulcanizing chamber, means are provided for separably connecting the plunger head with the cover and mold-carrying frame. The construction I use for this purpose is preferably as follows: The plunger head 7 has projecting from it, preferably at diametrically opposite points, a pair of slotted lugs or hooks 29, the plunger head being prevented from rotation by means of vertical guide bars 30 secured to the inner surface of the shell 1 between which the ends of the lugs or hooks 29 slide. Any other suitable means may be used for 100 this purpose if desired. Collars 31 are provided near the lower ends of two of the rods 21, beneath which the lugs or hooks 29 engage when the cover and rods depending therefrom are rotated. The lugs or hooks 105 are so located that when the cover is rotated so that its locking lugs 14 are disengaged from the lug 11 and are free to be lifted through the notches or slots 10, the rods 21 will be moved into the openings or slots in 110 the hooks or lugs 29 and the collars 31 will rest upon these hooks or lugs. The movement of the cover to unlock the same therefore automatically causes the cover and mold-carrying frame to be engaged with the 115 plunger head. This is the position of the parts shown in Figs. 2 and 4. As will be obvious, the plunger may now be raised, carrying with it the rods 21, cover 12, racks 25, grids or trays 27, each supported by its 120 proper set of shoulders thereon, and the molds 20 resting thereon, as shown in Fig. 1. The molds may then be removed laterally, one at a time, as they are brought up to a level with the loading and unloading table 125 32. When the molds have been discharged new ones may be placed upon the trays or grids in a similar manner, after which the plunger may be lowered until the parts are again in the position shown in Figs. 2 and 4, 130

when the cover is rotated to the position shown in Fig. 3. This action locks the cover in place, and also moves the depending frame so that it is disengaged from the 5 plunger-head, as indicated in the left-hand side of Fig. 3. The plunger head is now free to be forced upwardly between the bars 21 and racks 25 and caused to compress the several molds against the underside of the 10 cover, as indicated in Fig. 5. While in this position steam is forced into the vulcanizing chamber through a pipe 62 and the vulcanizing operation is performed. After the steam is discharged through a suitable pipe 15 connected with the outlet 63, the plunger is then lowered and again connected to the frame, as above described, in order that it may be utilized to discharge the molds from the press. A slight amount of play of the 20 cover longitudinally of the vulcanizer when locked is desirable in order to permit it to be easily locked and unlocked, and this end play is taken up by the internal pressure (of the ram in this instance, or of the steam if 25 its pressure is sufficient to lift the cover, or of both). The forcing of the cover outwardly against its stops has heretofore often been the cause of leakage of steam, particularly when the packing is mounted between 30 the transverse joint shoulders, so as to face longitudinally.

In order to seal the joint between the cover and the top of the shell and thus prevent the escape of the steam used to effect 35 the vulcanizing operation, I provide packing means, preferably of an expansible nature and so mounted as to be capable of closing the joint between the cover and shell and maintaining the same closed, even 40 though the cover is moved slightly relatively to the shell when the molds are forced against it by the pressure of the hydraulic ram. Such means in the preferred embodiment of my invention comprises a laterally- 45 facing packing ring 43 of peculiar construction mounted in a groove in the ring 8 at the top of the shell. This packing ring is made of rubber or other flexible material and is provided with a downwardly projecting lip 50 44 adapted to be laterally expanded (inwardly in this case) against a portion of the cover, such as the depending apron 45 thereof, which as here shown is cylindrical and projects within a concentric cylindrical 55 portion of the ring 8, in which the packing is mounted. The operation of this packing is automatic. It does not interfere with the lowering of the cover into position or with the rotation thereof, but when steam is admitted 60 to the vulcanizing chamber it enters the space 46 under the lip 44 and expands the latter into close engagement with the apron, effectually sealing the joint. It will be seen that when the molds are forced 65 against the underside of the cover, although

the latter is lifted slightly until the lugs 14 are forced firmly against the lugs 11, no leakage will occur, as the apron 45 will simply slide along the lip 44 without breaking the seal. As the packing ring engages a side 70 portion of the cover, it is not subjected to continual compression due to the weight of the cover and the compression of the cover upon its seat, or to possible damage by the seating of the cover. This improvement, 75 however, is not wholly limited to interfitting joint members of cylindrical form, nor to the mounting of the packing on the outer or stationary member, nor is it confined to vertical vulcanizers, or those using a ram which 80 exerts pressure against the cover or door.

In the drawings, and particularly in Fig. 7, I have illustrated an improved packing for the hydraulic ram. The top of the cylinder 4 is provided with a recess in which 85 is fitted a packing ring 50 of flexible material, a collar 51 being bolted to the cylinder to secure this packing ring in position. Back of the packing ring is a recess 52, into which open one or more ducts 53 leading 90 from an open recess 54 cut in the cylinder below the packing ring. The fluid-under-pressure in the cylinder enters the recess 54 and passes through the duct or ducts 53 into the recess 52, where it acts upon the packing 95 ring to force the same into engagement with the plunger. I prefer to make this packing ring of a number of layers of fabric 55, the fabric being preferably duck or muslin cut on the bias. The layers of fabric are frictioned, that is, thinly coated with rubber in order to hold them together, but are not impregnated with rubber to an extent sufficient to make them non-absorbent. A collar 51 is provided with a portion 56 adapted to 100 engage with the packing 50, with a flange adapted to be bolted to the cylinder in any suitable manner, as by bolts 58, and with a shoulder 59 adapted to engage a small packing ring 60 of biased fabric, rubber or other 105 suitable material. The parts are so proportioned that upon screwing down the bolts 58 the packing ring 60 will be firmly clamped between its seat and the shoulder 59, while the packing 50 will not be tightly compressed. When the ram has been packed and water is admitted into it, the water will enter the recess 54 and pass through the ducts into the recess 52, as above described, 110 when it will first force the packing 50 into close engagement with the plunger, after which it will gradually soak into the fabric forming the packing and cause the same to swell up and fit its seat tightly. The packing 60 prevents the leakage of fluid back 115 of the main packing. The lower wall of the seat for the packing 50 is preferably beveled as indicated at 61 in order to provide a space into which the packing may expand as it absorbs the fluid and swells up. 120 125 130

A very effectual packing is thus obtained, and one that is exceedingly durable. It is particularly suitable for use in a vulcanizing press as it is not injured by heat and may be located within the steam chamber of the vulcanizer, as shown, nor is it injured by the water used to operate the ram. It has heretofore been found necessary in vulcanizing presses of this character to provide 5 two packings, one, the main water packing, located in the ram cylinder outside of the steam chamber, and the other, an auxiliary steam packing, located within the chamber to prevent the leakage of steam to the water 10 packing and consequent injury thereto. As will be apparent, with my improved packing this is entirely unnecessary. I do not wish to be understood, however, as limiting myself to the use of my improved packing 15 only in connection with vulcanizing presses, for, although it is particularly adapted for such use, it possesses many advantages when utilized in other forms of apparatus.

In Fig. 4 I have shown a typical mold in 20 section containing a casing or shoe for a pneumatic tire. The mold illustrated comprises a pair of mold parts 33 suitably shaped to receive the tire casing, a ring or core 34 being utilized to support the interior 25 of the casing. As will be obvious, however, the press may be used with molds of other kinds adapted for the vulcanization of other articles than tires.

I claim:

- 35 1. In a vulcanizer, the combination of a vulcanizer body having an open end, a cover for closing said end, interlocking means upon said body and cover adapted to be operated by the relative rotation of the 40 two, means for exerting pressure within the vulcanizer tending to open the cover, and annular joint-forming members on said body and cover respectively, extending one within the other, one of said members having 45 a laterally-acting expandible packing ring engaging the complementary joint-forming member, whereby a limited outward movement of the cover is permitted without causing leakage.
- 50 2. In a vulcanizing press, in combination, a vulcanizer body having one open end and means for the admission of a vulcanizing fluid thereto, interlocking means at the open end of said body, a cover provided with 55 interlocking means adapted to be interlocked with the interlocking means on said body, the engagement of said interlocking means being loose so as to permit free engagement and disengagement thereof, a ram cylinder 60 at the opposite end of said body, a ram for clamping molds against said cover, and a flexible packing ring for closing the joint between said cover and said body, said ring being mounted in a groove in the inside of 65 said body and engaging a cylindrical side

surface of said cover, whereby a limited lifting of said cover by the action of said ram is permitted without causing leakage.

3. In a vulcanizing press, in combination, a vulcanizer body having one open end and means for the admission of a vulcanizing fluid thereto, interlocking means at the open end of said body, a cover arranged to be detachably interlocked with said body, a ram cylinder at the opposite end of said body, 70 a ram for clamping molds against said cover, and means for sealing the joint between said cover and body comprising a packing ring of flexible material mounted in a groove in said body having a lip projecting away from the open end of said body and adapted to be pressed into engagement with a cylindrical side surface of said cover by the pressure of the vulcanizing fluid contained in the body. 80

4. In a vulcanizing apparatus, a vulcanizer body having an open end, a cover for closing said end, interlocking means upon said body and cover adapted to be operated by the rotation of said cover upon said body, 90 and anti-friction means carried by said body for supporting said cover.

5. In a vulcanizing press, in combination, a vulcanizer body having an annular groove formed inside of the same near one end thereof, the upper wall of said groove being notched, a cover for closing the end of said body having lugs projecting therefrom adapted to pass through the notches, and to engage with portions of the upper wall of 100 said groove, said cover being rotatable to bring the lugs thereon into alignment with the said notches or with the portions of the upper wall of said groove between said notches, and anti-friction means for supporting said cover comprising balls mounted in a recess in the lower wall of said groove, and a retaining ring supported upon said balls. 105

6. In a vulcanizing press, in combination, a vulcanizer body, a ram for exerting pressure upon articles within said body, said ram comprising a cylinder, and a plunger operating in said cylinder, and a packing for said plunger, said packing comprising a ring of flexible material mounted in a seat at the upper end of said cylinder, said cylinder having a recess at the back of said seat, a second recess below said seat, and a duct connecting said recesses, said cylinder 110 also having a second seat above and outside of the seat for the main packing ring, an auxiliary packing ring mounted on said second seat, and a collar having portions engaging said main and auxiliary packing 115 rings. 120

7. In a vulcanizing press, in combination, a vulcanizer body, a cover having a portion projecting into said body and provided with means to interlock with the interior thereof, 125 130

clamping means adapted to force the molds against said cover, and a flexible packing ring engaging the side surface of the inwardly projecting portion of said cover whereby a limited lifting of the cover by said clamping means is permitted without occasioning leakage.

8. In a vulcanizing press, in combination, a vulcanizer body, a ram for exerting pressure upon articles within said body, said

ram comprising a cylinder and a plunger operating in said cylinder and a packing for said plunger, said packing comprising a layer of flexible material mounted in a seat about said cylinder, said cylinder having 15 a recess at the back of said seat, a second recess adjacent thereto, and a duct connecting said recesses.

JOHN R. GAMMETER.
